UNITED STATES PATENT OFFICE.

WENDELL WRIGHT, OF NEW YORK, N. Y.

MODE OF CONNECTING PIPES FOR STEAM-BRAKES.

Specification of Letters Patent No. 12,263, dated January 16, 1855.

To all whom it may concern:

Be it known that I, WENDELL WRIGHT, of the city, county, and State of New York, have invented certain new and useful Improvements in the Means of Applying Steam or Compressed Air to Operate Railroad-Brakes; and I do hereby declare that the following is a full, clear, and exact description of the same, reference being had to the accompanying drawings, forming part of this specification, in which—

Figure 1, is an inverted plan of the platform or framing of a car or locomotive having my improvements applied. Fig. 2, is a longitudinal vertical section of the same. Fig. 3, is a perspective view of the arrangement for regulating the force applied to the brakes. Fig. 4, is a front view of the indicator for indicating the degree of force applied. Fig. 5, is a longitudinal sectional view of one of the connections between the pipes which convey the steam or air from one car to the other. Fig. 6, represents a portion of Fig. 5, detached. Fig. 7, is an outside view of what is represented in Fig. 6. Fig. 8, is a transverse section in the line y, y' , of Fig. 6.

Similar letters of reference indicate corresponding parts in the several figures.

30 This invention consists in an improvement in the connections between the pipes which convey the steam or air under the cars to operate on pistons connected to the several brakes. Whereby the disconnected ends of 35 the pipes are always caused to be closed, but when the pipes are connected there is always caused to be an open communication between them.

To enable those skilled in the art to make 40 and use my invention I will proceed to describe its construction and operation.

A, is the platform of the car. B, B, are the trucks, to one of which the brakes are shown applied. The brakes themselves are not particularly represented, and will not be described here as they form a distinct and separate invention to form the subject of another application for a patent. It will be sufficient to say here in reference 50 to the brakes, that they are operated upon by turning a vertical shaft a , which is hung in suitable bearings under the car and carries a roller b , which winds up two cords or chains c, c' , and acts upon the brakes by drawing toward each other two bars d, d' , to which the brakes are attached. This

roller and cords or chains are a device in common use for operating the brakes heretofore employed and therefore constitute no part of my present invention, all of which is as much applicable to any other brakes as to those represented.

The power to turn the shaft a , to operate the brakes, is applied to an arm e , on the said shaft, through the rod f , of a piston working in a cylinder g , placed horizontally under the car. This cylinder is like those heretofore employed or proposed for operating brakes by steam or compressed air, being open at one end and closed at the other, and receiving the steam or air between the piston and the closed end, through a pipe, h , leading from the boiler if steam is used, or from a reservoir C if air is used, the said reservoir having a constant supply kept up within it by compression pumps worked from the locomotive or one of the car axles. Each car of the train will be furnished with a separate brake cylinder g , but all will be supplied with steam or air from the boiler or from the same reservoir C by a pipe i , which is so arranged as to be opened by the same means, and at the same time as the pipe h , when it is desired to put the brakes in action. The pipe i , is to communicate with a train 85 of pipe running under all the cars and leading to all the cylinders each car carrying its own length of pipe, and the several lengths of pipe being connected and disconnected at the same time as their respective cars, by 90 means of movable flexible connections. The first of these connections is shown in Figs. 1 and 2, and also in Fig. 5. These connections consist each of a piece of india rubber or other flexible tubing D , which is of such size 95 internally that the ends of the lengths of pipe i, i' , will fit it tightly when it is pushed over them by hand. The connecting tube D , is furnished at each end with a metallic mouth piece j , which serves to protect its 100 extremities. These mouth pieces may contain female screws to screw on the ends of the pipes i, i' , but this I do not at present think necessary.

Near the end of the pipe i , there is a valve 105 k , of conical form, so arranged that by the pressure of steam or air acting upon it, it may be made to close the pipe, and between this valve and the end of the pipe is a long spring, or elastic tongue l , shown tinted blue 110 in Figs. 5, 6 and 8. The outermost end of this spring, or end nearest the end of the

pipe is secured to the pipe by riveting or otherwise, and the other or innermost end occupies such a position that it is capable of pressing upon one side of the conical face of 5 the valve *k*. A part of the spring near the end of the pipe is bent so as to protrude through a slot *m*, in the pipe. When the end of the pipe is left free and uncovered by the connecting tube *D*, the spring *l*, lies 10 snugly up against the interior of the pipe as shown in Fig. 6, and in black outline in Fig. 8, but when the end of the pipe enters the connecting tube the protruding part of the spring *l*, coming in contact with the interior 15 of the metallic mouth piece *j*, of the tube, is forced inward and the spring is thus caused to move toward the center of the tube as shown in Fig. 5, and in red outline in Fig. 8 and its innermost end caused to impinge 20 upon one side of the face of the valve, which by reason of its conical form is driven back from its seat by the impinging action of the spring and the end of the pipe thereby left open. Each end of each length of pipe *i'*, 25 belonging to the other cars, is to be furnished with a similar valve and spring so that when it is uncovered by the connecting tube it will be closed, and when covered by

the said tube will be open. Hence if proper care is taken when one or more cars are detached from a train, to remove along with the detached car the connecting tube which connected its length of pipe *i'*, with the length belonging to the last car remaining attached to the train, the rear end of the 30 train of pipe must be always closed; but when another car is again attached it cannot fail to be opened by the valve being thrown back by the action of the mouth piece upon the spring tongue *l*. 35

What I claim as my invention and desire to secure by Letters Patent is—

Providing each end of the several lengths of pipe for conveying the steam or compressed air under the cars, with a valve *k* 45 and an elastic or movable tongue *l*, applied substantially as described so as to allow the valve to be closed by the pressure of the steam or air when the end of the pipe is disconnected, but to be caused to open the valve 50 by the entrance of the end of the pipe into the mouth piece of the connecting tube *D*.

WENDELL WRIGHT
